COMBINED STAND, TRAY, AND GLASS HOLDER

Morris Mark, Los Angeles, Calif.

Application March 26, 1957, Serial No. 45,439

Term of patent 3½ years

(Cl. D33—14)

Fig. 1.

Fig. 2.

Fig. 3.

Fig. 1 is a side elevational view of a combined stand, tray and glass holder showing my new design.

Fig. 2 is a plan view thereof.

Fig. 3 is a cross-sectional view as taken on the line 3—3 of Fig. 1.

The dominant features of my design reside in those portions shown in full lines on the drawing.

I claim:

The ornamental design for a combined stand, tray and glass holder, substantially as shown and described.
